LADY'S FOUNDATION UNDERGARMENT

Eileen A. Rockwell, Bridgeport, Conn., assignor to The La Resista Corset Company, Bridgeport, Conn., a corporation of Connecticut

Application January 25, 1951, Serial No. 13,947

Term of patent 14 years

(Cl. D20—2)

To all whom it may concern:

Be it known that I, Eileen A. Rockwell, a citizen of the United States, residing at Bridgeport, in the county of Fairfield, and State of Connecticut, have invented a new, original, and ornamental Design for Lady's Foundation Undergarment, of which the following is a specification, reference being had to the accompanying drawing, forming part thereof.

In the drawings:

Fig. 1 is a plan view in flattened position of the lady's foundation undergarment, showing my new design, the broken ends being normally connected.

Fig. 2 is a perspective view from the front, showing the same in its worn position.

Fig. 3 is a perspective view from the rear, also showing the same in its worn position.

The shaded areas indicate elastic woven material of contrasting surface texture from the adjacent areas.

I claim:

The ornamental design for a lady's foundation undergarment, substantially as shown and described.

EILEEN A. ROCKWELL.
